UNITED STATES PATENT OFFICE.

GEORGE H. VIANCOUR, OF CLEVELAND, OHIO, ASSIGNOR OF ONE-THIRD, BY DIRECT AND MESNE ASSIGNMENTS, TO CHARLES A. BACHMAN AND ONE-THIRD TO WILLIAM L. LLOYD, OF CLEVELAND, OHIO.

SHAVING-CUP.

No. 864,274.

Specification of Letters Patent.

Patented Aug. 27, 1907.

Application filed March 12, 1906. Serial No. 305,530.

To all whom it may concern:

Be it known that I, GEORGE H. VIANCOUR, a citizen of the United States, and a resident of Cleveland, county of Cuyahoga, and State of Ohio, have invented 5 a new and useful Improvement in Shaving-Cups, of which the following is a specification, the principle of the invention being herein explained and the best mode in which I have contemplated applying that principle, so as to distinguish it from other inventions.

10 My invention relates to shaving cups, and is especially designed to be an improvement in such class of devices which is very sanitary and may be conveniently and readily cleansed.

Said invention consists of means hereinafter fully 15 described and specifically set forth in the claims.

The annexed drawing and the following description set forth in detail certain mechanism embodying the invention, such disclosed means constituting but one of various mechanical forms in which the principle of the 20 invention may be used.

In said annexed drawing: Figure 1 represents a side elevation of my improved shaving mug, with the discharge spout upon the bottom thereof, and some adjacent parts shown in vertical section. Figs. 2 and 3 are 25 broken central vertical sections of the same taken upon the plane indicated by the line 2—2, Fig. 1, Fig. 2 showing a bottom which is longitudinally movable of the body of the cup in its open position, and Fig. 3 showing said bottom in its closed position. Fig. 4 represents a transverse section taken upon the plane indicated by the line 4—4, Fig. 1.

The body of my improved shaving cup is designated by the reference character A and has a suitable handle a, a bottom a' provided with perforations a², and a plurality of lugs a³ preferably disposed in an annular ring and projecting upwardly from the upper portion of said bottom a', as plainly shown in the drawing. The side portion of the body is not continuous from top to bottom, but near its lower portion is turned in at a suitable 40 angle, preferably a right angle as shown, thus forming an inner annular shoulder a⁴. Secured near the lower part of the side of the body A are outwardly-projecting pins a⁵, two as shown, diametrically disposed relatively to each other.

45 A bottom member is designated by the reference character B and has an imperforate bottom portion proper b and a side portion b' that exteriorly slidably engages the body-portion A, being provided with an angular part b², similar and complementary to the part a⁴ of the body-portion A. Said bottom B is provided with two upwardly-extending ears b³, each having an angular slot or groove comprising a substantially vertical portion b⁴ and a substantially horizontal portion b⁵, such slots being adapted to receive and retain the pins

a⁵ secured to the body portion A, which pins travel in 55 said slots as will be hereinafter fully explained. It will, of course, be understood that it is immaterial whether the pin-engaging means shown as comprising such two continuous slots b⁴ b⁵ be actually an opening of the character described or simply a groove on the inner side of 60 the ears. Accordingly the term slot as used hereafter is intended to connote both forms of such engaging means or their equivalent. Secured to the upper parts of the ears b³ respectively by means of pins b⁶ are hooks b⁷. As plainly shown in Figs. 1 and 4, said bottom B is provided with a discharge spout b⁸, having an upwardly-turned overflow portion b⁹. Disposed between the parts a⁴ and b² of the body A and the bottom B respectively, and secured to the part a⁴, is an annular packing-ring C preferably of rubber. 70

The elements of my invention coöperate as follows: When the cup is being used, the bottom B fits tightly up against the bottom a' of the body portion A, the parts being retained in such position by means of the disposition of the pins a⁵ in the horizontal portion b⁵ of 75 the angular slots, as shown in Fig. 1. When the cup has been used and it is desired to cleanse the same, the bottom B and the body-portion A are turned relatively to each other by simply grasping the lower portion of the bottom B and turning the same upon the bottom a', 80 the pins a⁵ thus traveling in the horizontal portion b⁵ of the angular slots to the lower part of the vertical portion b⁴, and then the bottom B drops away from the bottom a', as shown in Fig. 2, the pins a⁵ traveling to the top of the vertical portion b⁴ of the slots, thus holding 85 the bottom B to the body portion A, as plainly shown in Fig. 2. The shaving soap is retained in the cup above the bottom a' upon the annular series of lugs a³. Water from any suitable source, such as a faucet, can be turned into the cup when the body portion A and 90 the bottom portion B are disposed relatively to each other, as shown in Fig. 2, thereby flushing out the cup, the waste water being allowed to escape through the discharge spout b⁸ and over the overflow portion b⁹ thereof, the pins a⁵, slots b⁴, and ears b³ pivotally connecting the bottom B and body portion A together, as will be readily understood, thus enabling such discharge of the wash water. When the cup is not in use, and it is desired to dry and air the same and the soap 95 therein, the bottom B is retained in its open position by means of the hooks b⁷, which engage with and hold the pins a⁵ in the upper part of the vertical slots b⁴, so that when the cup is set down the bottoms B and a' will not come into juxtaposition. A satisfactory and watertight joint is secured between the bottoms B and a' by 100 means of the annular rubber ring C, as will be readily understood.

It should be particularly noted that my improved

shaving cup is very sanitary, that it can be quickly and conveniently washed and flushed, the barber simply, while holding the cup by the handle *a* in the one hand, turning the bottom *B* with the other hand as he walks 5 toward the faucet, and thus having allowed the bottom *B* to fall in its lowermost position, shown in Fig. 2, he can release the same, since said bottom is permanently secured to the bottom portion *a'*, and then turn on the water to flush the cup with the same hand by which he 10 turned the bottom *B* to bring it to its open position. The flush water can be discharged immediately, as will be readily understood, and the operation is thus quickly and effectively accomplished. I have provided the discharge spout *b*⁸ with the upwardly-turned portion 15 *b*⁹, plainly shown in Fig. 1, in order that the wash water may be retained in the bottom *B*, until such time as the operator desires to positively discharge the same, and thus said wash water will not commence to run out of the bottom *B* as soon as it is received into the same, 20 which would be the case if the discharge spout were simply a straight opening or outlet from the bottom *B*.

Having thus described my invention in detail, that which I particularly point out and distinctly claim is:

1. A shaving-cup comprising a body-portion having a 25 bottom adapted to retain a cake of soap but to permit the free passage of liquid therethrough, and a bottom member adapted to be held in contact with said body portion to close the bottom thereof.
2. In a shaving-cup, the combination with a body, of a 30 bottom member slidably attached to said body so as to be longitudinally movable thereof, said member being adapted in its upper position to close said body and in its lower position to pivotally depend from the same.
3. In a shaving-cup, the combination with a body having 35 a perforated bottom, of a bottom member slidably attached to said body so as to be longitudinally movable thereof, said member being adapted in its upper position to close such perforated bottom and in its lower position to pivot-

ally depend from said body, and means adapted to retain said member in each of said positions, respectively. 40

4. In a shaving-cup, the combination with a body, of a 45 bottom member transversely pivotally attached to said body and longitudinally movable thereof.

5. In a shaving-cup, the combination of a suitable body having a perforated bottom; pins secured to said body; and a second bottom adapted to contact with such perforated bottom, said second bottom being provided with upwardly extending ears having angular slots in which said pins, respectively, are adapted to travel and be retained. 50

6. In a shaving-cup, the combination of a suitable body having a handle and a perforated bottom; pins secured to said body; a second bottom provided with upwardly extending ears having slots in which said pins respectively are adapted to travel and to be retained; and hooks secured to said ears, respectively, and adapted to engage and hold said pins, respectively. 55

7. In a shaving-cup, the combination of a suitable body having a handle and a perforated bottom; pins secured to said body; a second bottom provided with upwardly extending ears having slots in which said pins respectively, 60 are adapted to travel and to be retained; and an annular packing ring disposed intermediately of said two bottoms.

8. In a shaving-cup, the combination of a suitable body having a handle and a perforated bottom; pins secured to said body; a second bottom provided with upwardly extending ears having slots in which said pins respectively, 65 are adapted to travel and to be retained; and soap-holding means secured to the upper portion of said perforated bottom.

9. In a shaving-cup, the combination of a suitable body 70 having a handle and a perforated bottom; pins secured to said body; a second bottom provided with upwardly extending ears having slots in which said pins respectively, are adapted to travel and to be retained, said second bottom having a discharge spout.

Signed by me, this 7th day of March 1906.

GEORGE H. VIANCOUR.
